ROTARY HYDRAULIC CLUTCH

John S. Becker, Rochelle Park, N. J., assignor to
 BENDIX AVIATION CORPORATION, South Bend, Ind.,
 a corporation of Delaware

Application November 23, 1942, Serial No. 466,640

3 Claims. (Cl. 60—54)

1

This invention relates to hydraulic apparatus and particularly to the establishment and control of a hydraulic type of driving connection or transmission for transfer of energy from a driving member to a member to be driven.

An object of the invention is to provide a novel type of hydraulic transmission characterized by the ability of the mechanism to adjust itself automatically to variations in the conditions imposed thereupon, and in such a manner as to produce at the driven end of the unit a substantially constant speed or a substantially constant torque output, according to which is preferred in any given installation.

Another object of the invention is to provide a novel hydraulic transmission of the type including a pair of fluid receiving members rotatable about a common axis and adapted to occupy varying relative positions in response to variations in the speed of the driving member.

These and other objects of the invention will become apparent from inspection of the following specification when read with reference to the accompanying drawings wherein are illustrated two embodiments of the invention. It is to be expressly understood, however, that the drawings are for the purpose of illustration only, and are not designed as a definition of the limits of the invention, reference being had to the appended claims for this purpose.

In the drawings:

Fig. 1 is a longitudinal sectional view of a device representing one embodiment of the invention;

Fig. 2 is a transverse view looking into one of the two complementary sections of the unit shown in Fig. 1;

Fig. 3 is a longitudinal sectional view of a device representing a second embodiment of the invention; and

Fig. 4 is a transverse sectional view along the line 4—4 of Fig. 3.

Referring first to Figs. 1 and 2, there is disclosed therein a housing having complementary sections 5 and 6 provided with registering flanges 7 and 8 suitably secured as indicated at 9, and further provided with hub portions 11 and 12, respectively, the former being journaled upon the driving shaft 13, as indicated at 14, and sealed, as by a packing gland, to the right of the journal 14, as shown, while the hub 12 is drivably connected by means of the key 16 to the driven shaft 17; the latter being counterbored to form a bearing portion 19 to receive the reduced end portion 21 of the driving shaft 13.

2

Within the housing sections 5 and 6 there is provided a pair of fluid receiving vessels 26 and 27, each equipped with radially disposed vanes as indicated at 28 and 29, respectively, so that the two units constitute complementary impellers or rotors corresponding to those employed in a conventional type of fluid clutch, and the disposition of the units 26 and 27 being such that upon rotation of the driving shaft 13 (and therefore corresponding rotation of the driving impeller 26 which is keyed to the shaft 13, as indicated at 31) liquid within the housing 5—6 will be picked up by the pockets formed in the impeller 26 by the vanes 28 and thrown from said pockets into the oppositely disposed pockets formed by the vanes 29 in the driven rotor 27, thereby causing a rotation of the said driven rotor 27 and—in view of the physical connections between the driven rotor 27 and the housing member 6—a corresponding rotation of the housing 5—6, thus producing rotation of the driven shaft 17.

The novel means whereby the speed of rotation of the driven shaft 17 is maintained substantially constant, notwithstanding variations in the speed of the driving shaft 13, will now be described. At angularly spaced intervals about the periphery of the driven rotor 27 there are provided radially extending fins or ribs 33 adapted to register with longitudinally extending tracks or splines 34 formed at corresponding intervals about the inner surface of the housing section 6 and constituting channels along which the ribs 33 may slide in a direction parallel to the axis of rotation, while at the same time constituting the mechanical connection whereby the rotation of the driven rotor 27 is transmitted to the housing 5—6 and thence to the driven shaft 17. Also formed in the housing section 6 are a plurality of cylindrical recesses or pockets 38 corresponding in number and angular spacing to the number and angular spacing of the ribs 33, and each of said cylinders containing a piston or a plunger 39 having positive connection with a corresponding one of the ribs 33. As shown, the positive connections for each plunger and its associated rib include a rod 41 suitably secured to the piston at one end, as indicated at 42, and also securely fastened at its other end within a tapped hole or other suitable receiving means provided in a boss 43 forming an integral part of each rib 33 or of the housing of the driven rotor 27 at the points of formation of the said ribs 33. Each cylinder 38 is further provided with a coiled, partially compressed spring 51.

having abutment against the piston 39 at one end while its other end rests against the end wall of the cylinder, as shown. Intermediate the said end wall and the piston there is provided in each cylinder a radially extending aperture 53 constituting a vent to prevent formation of a vacuum behind the piston.

In operation of the embodiment of the invention shown in Figs. 1 and 2, as the impeller 26 starts to turn it drives housing 5-6, thereby setting up a hydraulic pressure on the periphery of the housing, due to the centrifugal force imparted to the oil. As the pressure increases, it tends to force pistons 39 to outer end of cylinders 38 against springs 51, moving the driven rotor 21 away from impeller 26. This increases the "slip" between the two impellers, so that any increase in speed of impeller 26 is taken up by a corresponding increase in slip. The result is substantially constant speed at the shaft 17. The slip may be controlled by adjusting the load on springs 51 in any suitable manner.

Turning now to the embodiment shown in Figs. 3 and 4, wherein corresponding elements are designated by reference numerals corresponding to those employed in Figs. 1 and 2, there is shown a modified type of driven rotor wherein the said driven rotor is in the form of a series of angularly spaced vanes 61 of L-shaped cross-section; the vanes being pivotally mounted in bearings 62 formed integral with the housing section 6 and also pivotally mounted at their inner ends in bearings 63 extending laterally from the hub portion 12 of the housing section 6. A set of coiled compression springs 67 have engagement with one face of each of the vanes 61 and bear at their opposite ends against the wall of the housing section 6, the said springs acting to hold the vanes in the relative disposition indicated in Fig. 3, namely, in approximate alignment with the oppositely disposed vanes 28 of the driving impeller 26; but as the speed of rotation increases—which increased speed would otherwise create a tendency for a correspondingly increased torque output at the driven shaft 17—the resulting increase in fluid pressure exerted against the vanes 61 will tend to turn the said vanes about their bearings 62 and 63 thereby producing a greater degree of compression of the springs 67. As such turning of the vanes occurs the amount of relative rotation or slip, as between the driving impeller 26 and the driven vanes 61, will increase due to the increase in the gap between the opposing edges of the vanes 28 on the one hand and the now receding edges of the vanes 61 on the other. This increase in slip will in turn reduce the fluid pressure being exerted upon the vanes 61, thereby offsetting what would otherwise be the tendency toward increased torque at the driven shaft 17. Thus is produced an action by reason of which the torque output at the driven shaft 17 is maintained substantially constant.

In the embodiment shown in Figs. 1 and 2, rollers 35 are provided to facilitate free shifting of ribs 33 along channel tracks 34.

What is claimed is:

1. In a hydraulic transmission, a housing, a driving impeller member mounted in said housing, a driven rotor member mounted in said housing, fluid pressure responsive means carried by

said housing to maintain said driven rotor member in rotation at substantially constant speed, said means comprising a plurality of pistons disposed within the circumferential confines of said housing and exposed to and movable by the pressure developed in said housing, means for connecting said pistons to said rotor member to impart their movement to said rotor member, and means disposed circumferentially about said rotor member and slidably connecting the latter to said housing for longitudinal movement relative to said housing.

2. In a hydraulic transmission, a housing provided with a plurality of longitudinal guideways on its interior face, a drive shaft rotatably mounted in said housing, an impeller member fixed to said drive shaft, a rotor member loosely mounted on said drive shaft and provided with means coating with said guideways to effect longitudinal guiding movement of said rotor member with respect to said housing, and fluid pressure responsive means to maintain said rotor in rotation at substantially constant speed, said means comprising a plurality of pistons arranged within said housing and exposed to and movable by the pressure developed in said housing, and means for connecting said pistons to said rotor member to impart their movement to said rotor member.

3. In a hydraulic transmission, a housing, a driving impeller member mounted in said housing, a driven rotor member mounted in said housing, fluid pressure responsive means carried by said housing to maintain said driven rotor member in rotation at substantially constant speed, said means comprising piston means or the like disposed within the circumferential confines of said housing and exposed to and movable by the pressure developed in said housing, means for connecting said piston means to said rotor member to impart movement of the piston means to said rotor member, and means connecting the latter to said housing for longitudinal movement relative to said housing.
